US00D915885S

(12) **United States Design Patent** (10) **Patent No.:** **US D915,885 S**
Costle et al. (45) **Date of Patent:** **** Apr. 13, 2021**

(54) **AEROSOL DISPENSING CAP**(71) Applicant: **ILLINOIS TOOL WORKS INC.**,
Glenview, IL (US)(72) Inventors: **Carey Christopher Costle**, Tucson, AZ
(US); **Stephen Edward Richey**,
Atascadero, CA (US); **Brendan
Sangster**, San Luis Obispo, CA (US)(73) Assignee: **ILLINOIS TOOL WORKS INC.**,
Glenview, IL (US)(**) Term: **15 Years**(21) Appl. No.: **29/684,318**(22) Filed: **Mar. 20, 2019**(51) LOC (13) Cl. **09-07**

(52) U.S. Cl.

(Continued)

Primary Examiner — Wendy L Arminio(74) *Attorney, Agent, or Firm* — Pauley Erickson &
Swanson(57) **CLAIM**The ornamental design for an aerosol dispensing cap, as
shown and described.**DESCRIPTION**FIG. 1 is a rear perspective view of the aerosol dispensing
cap, according to the invention;FIG. 2 is a front perspective view of the aerosol dispensing
cap shown in FIG. 1;FIG. 3 is a rear view of the aerosol dispensing cap shown in
FIG. 1;FIG. 4 is a front view of the aerosol dispensing cap shown
in FIG. 1;FIG. 5 is a side view of the aerosol dispensing cap shown in
FIG. 1;FIG. 6 is a top view of the aerosol dispensing cap shown in
FIG. 1; and,FIG. 7 is a bottom view of the aerosol dispensing cap shown
in FIG. 1.The broken lines depict portions of the aerosol dispensing
cap that form no part of the claimed design.**1 Claim, 7 Drawing Sheets**| (56)	References Cited
